UNITED STATES PATENT OFFICE.

CHARLES F. SPAULDING, OF ELIZABETH, NEW JERSEY.

BRIDGE-INDICATOR FOR BILLIARD-TABLES.

SPECIFICATION forming part of Letters Patent No. 317,871, dated May 12, 1885.

Application filed October 28, 1884. (No model.)

To all whom it may concern:

Be it known that I, CHARLES F. SPAULDING, of Elizabeth, in the county of Union and State of New Jersey, have invented a new and useful Improvement in Bridge-Indicators for Billiard-Tables, of which the following is a full, clear, and exact description.

Reference is to be had to the accompanying drawings, forming a part of this specification, in which similar letters of reference indicate corresponding parts in all the figures.

Figure 1 is a side elevation of a part of a billiard-table to which my improvement has been applied. Fig. 2 is a plan view of a billiard-table upon a reduced scale. Fig. 3 is an end elevation, partly in section, of a corner of a billiard-table to which my improvement has been applied.

The object of this invention is to facilitate finding the bridge in playing billiards, and thereby promote the convenience of billiard-players.

The invention consists in the combination, with a billiard-table, of sliding bars, sliding hooks, and a connecting mechanism, whereby the weight of a bridge-handle is made to raise the upper ends of the said sliding bars above the tops of the table-rails. The sliding hooks and the sliding bars are connected by cords or chains passing around guide-pulleys, whereby the said hooks and bars are made to move at the same time and in opposite directions, as will be hereinafter fully described and then claimed.

A represents a billiard-table, at the end parts of the sides of which are placed hooks B, to receive the handles C of the bridges D, and support the said handles in such positions that they can be readily grasped by the players when the said bridges are to be used. The shanks of the hooks B slide in keepers E, attached to the lower parts of the sides of the table A, and to the upper ends of the said shanks are attached the ends of small cords or chains F, which pass over guide-pulleys G, pivoted to lugs formed upon the keepers E, and over guide-pulleys H, pivoted to lugs formed upon plates I, attached to the under sides of the side rails of the table A. The

other ends of the cords or chains F are attached to the lower ends of small bars J, which pass up through perforations in the side rails of the table A, so that their upper ends can project a little above the tops of the said rails, as shown in Figs. 1 and 3. The bars J are made a little heavier than the hooks B, so that when the said bars and hooks are left free the said bars will move downward, raising the said hooks. The upward movement of the hooks B is limited by stop-pins K, attached to them, and which come in contact with the keeper E when the upper ends of the bars J are flush with the top of the table-rails. When the handles C of the bridges D are laid upon the hooks B, as shown in Figs. 1 and 3, the said hooks B are drawn downward, raising the bars J, and causing their upper ends to project above the tops of the table-rails, as shown in Figs. 1 and 3, so that the players can see the said projecting ends of the bars J, can thus know where the bridges are, and can take hold of the handles of the said bridges without removing their eyes from the table. The upward movement of the bars J is limited by stop-pins L, attached to the said bars J, and which come in contact with the plates I, as shown in Fig. 3.

Having thus described my invention, I claim as new and desire to secure by Letters Patent—

1. The combination, with a billiard-table, of the sliding bars J, the sliding hooks B, and a connecting mechanism, substantially as herein shown and described, whereby the weight of a bridge-handle is made to raise the upper ends of the said sliding bars above the tops of the table-rails, as set forth.

2. The combination, with the table A, the sliding hooks B, and the sliding bars J, of the cords or chains F and the guide-pulleys G H, substantially as herein shown and described, whereby the said hooks and bars are made to move at the same time and in opposite directions, as set forth.

CHARLES F. SPAULDING.
